UNITED STATES PATENT OFFICE.

EZRA E. SMART, OF HARTFORD, CONNECTICUT.

COMBINATION POCKET TOILET ARTICLE.

Application filed January 21, 1924. Serial No. 687,486.

To all whom it may concern:

Be it known that I, EZRA E. SMART, a citizen of the United States, and a resident of Hartford, in the county of Hartford, 5 State of Connecticut, have invented certain new and useful Improvements in a Combination Pocket Toilet Article, of which the following is a specification.

This invention relates to a toilet article comprising, in combination, a comb, brush and mirror particularly adapted to be carried in the pocket of the user.

The object of the invention is to provide an improved construction and arrangement 15 of parts for a toilet article of this sort.

Another object of the invention is to provide an improved toilet article of this character which is extremely simple in construction, which may be manufactured and sold 20 at a relatively low cost, which is handy and convenient in use, and which is extremely compact so that, when folded up, it occupies but very small space, thus permitting it to be conveniently carried in the pocket 25 of a vest or the like.

Another object of the invention is to provide a combination of elements wherein the brush constitutes a receptacle for receiving the mirror and also as a support 30 to which the comb is pivoted. The brush also constitutes a handle both for the brush itself and for the comb.

Other objects will be in part obvious and in part pointed out hereinafter.

The invention accordingly consists in the features of construction, combination of elements and arrangement of parts which will be exemplified in the construction herein-after set forth, and the scope of the application of which will be indicated in the appended claims.

In the drawing forming a part of this specification and in which similar reference characters refer to similar parts,

Figure 1 is an elevational view of my improved article with the comb shown in partly open position. The comb also is shown in dotted lines in the position which it takes when the article is folded up;

Fig. 2 is an end view;

Fig. 3 is a view looking at the back of the brush and showing the mirror in place thereon; and

Fig. 4 is a sectional view taken substantially on line 4-4 of Fig. 3.

Referring to the drawing, *a* designates

the body portion of the brush provided with brush bristles *b*. *c* designates the comb pivoted to the brush body *a*, and *d* is the mirror adapted to be slid into place in the back 60 of the brush body.

The body portion *a* of the brush may be constructed of any suitable material, for instance, rubber, celluloid, or aluminum. If desired, the body *a* may be cast, but it is also capable of being formed of sheet metal. The brush bristles may be secured to the body in any approved manner. The back of the body has an undercut groove into which the mirror *d* is adapted to be slipped. 70 This groove is formed by providing the body *a*, along its marginal edges, with in-turned flanges or guides 10. The mirror *d* is of rectangular shape and fits closely within the groove provided by the flanges 10. 75 The mirror may have at one end a nail notch 11 for facilitating the withdrawal of the mirror from place. Pivoted to that face of the brush provided with the bristles is the comb *c* which may be of any desired shape and formed of any suitable material. 80

This comb may be stamped from sheet metal. The comb has, at one end, a generally round portion 13 which bears against a semi-circular extension 14 at the end of 85 the brush. The comb may be pivoted to this extension in any desired manner, as by means of a rivet 15. For the purpose of limiting the opening movement of the comb, the latter has a shoulder 16 which is adapted to abut against a projection 17 on the brush body.

When my improved toilet article is not in use, the mirror *d* is positioned in the groove in the back of the brush, and the comb overlies the brush body with the teeth of the comb nestled among the bristles, as shown most clearly by dotted lines Fig. 1 and by full lines Fig. 2. When in this condition, the article is very compact and, therefore, requires but slight space. If desired, it may be enclosed in a casing and the entire assembly may be carried around in the pocket of a vest or coat. When it is desired to use the article, the comb is swung 95 into open position, and the mirror is removed. Then, while looking into the mirror, the user may comb his hair and then brush it. When the comb is used, the brush may be grasped in the hand and the comb held in extended position, that is, with the shoulder 16 thereof against the projection 100 105 110

17 of the brush. The brush thus serves as a handle for the comb. The brush, itself, is used in the same manner as an ordinary brush.

5 As many changes could be made in the above construction and many apparently widely different embodiments of this invention could be made without departing from the scope thereof, it is intended that 10 all matter contained in the above description or shown in the accompanying drawing shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

20 I claim as my invention:

1. A pocket toilet article comprising, in combination, a relatively thin brush, and a comb pivoted at one end of said brush and 25 adapted to overlie the brush with its teeth nested among the bristles.

2. A pocket toilet article comprising, in

combination, a brush body provided on one surface with brush bristles, a comb, means for pivoting one end of said comb to one end of said brush body, said comb being adapted to overlie said brush body with the teeth of the comb nestled among the bristles, and interengaging means between said comb and brush body for limiting the extent of opening movement of the comb relative to the brush.

3. A pocket toilet article comprising, in combination, a brush having a brush body provided on one face with bristles and on its back with a groove, a rectangular shaped mirror adapted to be slipped in place in said groove, a comb, a rivet for pivoting said comb to said body portion of said brush, said comb being adapted, when in closed position, to overlie said body portion with the teeth of the comb nestled among said bristles, said comb having a shoulder and said body portion having a projection against which said shoulder is adapted to engage, whereby the opening movement of said comb is limited.

EZRA E. SMART.
